CONCEALED HINGE FOR MOTOR VEHICLE
BODIES

Valere M. Naert, Detroit, Mich.

Application June 1, 1936, Serial No. 82,896

2 Claims.

(Cl. 16—135)

The present invention relates to improvement in hinges adapted for motor vehicle bodies and the principal object thereof is to provide a certain hinge structure arranged so that when the doors 5 of the vehicle are closed there will be no projected or exposed portions of the hinges, thus avoiding this unsightly condition.

Another advantage of the invention is that it is scientifically designed with exacting proportions whereby the principal parts thereof may be composed of metal stampings, thus eliminating the necessity of castings and the like for this purpose, as in the commonly known hinges of this type.

Still another advantage of the invention is the fact that the particular construction thereof permits a greater passage within the body entrance when the doors are open, or in other words, the space is increased by approximately three inches 20 greater than the corresponding space when the doors are open in the ordinary types of door hinges.

It will become readily apparent during the course of the following detailed description and 25 throughout the accompanying drawings, that the invention possesses advantages which are more fully pointed out in the appended claims.

With reference to the drawings:

Figure 1 is a partial exterior view of a vehicle 30 body and pillar showing how it will appear with the improved hinges completely concealed and invisible from the exterior of the vehicle.

Figure 2 is a full size view of one member 35 of the hinge with part thereof in section as indicated.

Figure 3 is a full size view of the second member of the hinge.

Figure 4 is a section taken along the line 4—4 of forthcoming Figure 9, and showing the 40 hinge in a closed position of the door.

Figure 5 is a similar section to Figure 4, but showing the hinge in an open position of the door.

Figure 6 is a vertical section taken upon the line 6—6 of Figure 4.

Figure 7 is a view in elevation looking at the inner edge of the door and showing the hinge members secured thereto.

Figure 8 is a vertical sectional view taken upon the line 8—8 of forthcoming Figure 9.

Figure 9 is a rear elevation of the assembly 50 with the door broken away as indicated.

Figure 10 is a transverse sectional view taken upon the line 10—10 of Figure 1.

In further disclosing my invention, it is to be 55 understood that certain elements directly asso-

ciated with the same but not a part thereof will be designated by consecutive alphabetical letters, while the invention proper will be characterized by the customary reference numerals.

The invention comprises a hinge member 1 having a body which is curved transversely as shown in Figures 4 and 5, one end portion of said body being deflected and bent inwardly to form an eye or knuckle 2. The opposite end portion 3 of said body is elongated and formed with a particular sweep adapting it to fit in the longitudinally extending recess A formed in the edge face of the door where it is secured by screws 4 and 4A which pass through countersunk openings 6 formed in the attaching end of the body. An opening 5 is provided to accommodate a screw driver when applying the screw 4A.

It is noted that a reinforcement plate C is provided and is welded to the back of said recess for the accommodation of screws 4 and 4A.

Opening D is provided where shown in the pillar E of the door frame so as to permit the passage of body 1 therethrough as indicated.

In Figure 3 it is seen that edge 7 of the member 1 is cut diagonally to conform to the vertical curvature of door B, and in this manner it will fit snugly in place against the door with ample rigidity in relation thereto.

The companion hinge member 8 has a body which is curved transversely to provide a portion 9 adapted to engage the inner surface of pillar E as shown in Figures 4 and 5 where it is welded to hold it firmly thereto in this relation. Knuckles 10 are formed upon the member 8 in vertical spaced relation to each other and have vertical passages 11 therethrough so as to permit the passage of a vertically disposed pin 12, and it is understood that the knuckle 2 of the hinge member 1 will be in axial alignment with knuckles 10 when the hinge is assembled, said 40 pin passing through both the knuckles 2 and 10.

In view of the curvature of the pillar E the recess A sweeps to a greater depth in the center of its length as at 13 in Figure 9, so as to provide proper clearance intermediate the pillar and door 45 at this location thereof.

In Figure 8 it is seen by the center line therein that the hinges are in true vertical and axial alignment with each other, also in the position of Figure 9 center line 14 indicates the vertical alignment of the hinges, and center line 15 indicates the center of pillar E. In this manner it is clearly understood that the hinges will operate accurately with the proper amount of clearance, and that they provide adequate strength readily 55

applicable to any type of door, even to the most massive ones adapted for vehicle bodies of any type or design.

While the invention is primarily designed so 5 as to accommodate vehicle bodies, the same would be as equally advantageous when applied to wall cabinets or the like, or in fact any place where hinged doors are required.

It is obvious in conclusion that the disclosure 10 herewith is merely illustrative in its substance so as to reveal the general principle of the invention with no limitations upon the design or the proportion thereof consistent with marketable requirements.

15 Having thus fully described my invention, what I claim as new is:

1. A hinge for mounting a door for outward swinging movement from a closed position in a door frame at a side of a channelled door jamb 20 to an opened position with its hinged edge face confronting the outer wall of the jamb, said hinge comprising a transversely curved jamb-engaging member and a door-engaging member pivotally connected at one side with the jamb- 25 engaging member, the jamb-engaging member being adapted to be mounted in the channelled

jamb against the inner face of said outer wall thereof, and the door engaging member being substantially U-shaped in transverse cross section and together with the jamb engaging member extending conjointly in a spiral path, the 5 door engaging member being adapted to extend from its pivoted side through a side wall of the jamb in overlapping relation to the side edge of the jamb-engaging member opposite the pivotal connection between the members and secured to 10 the side edge face of the door confronting said side wall of the jamb when the door is closed.

2. A hinge comprising a jamb engaging member and a door engaging member pivoted along one side to a side of the jamb engaging member, 15 said members being curved transversely and having their lines of curvature extending conjointly in a spiral path with the jamb engaging member disposed between side portions of the door engaging member whereby the door engaging 20 member is disposed in straddling relation to the jamb engaging member and may have swinging movement about the jamb engaging member transversely thereof.

VALERE M. NAERT. 25
